(57) **CLAIM**

The ornamental design for a portable lamp with detachable stand, as shown and described.

DESCRIPTION

FIG. 1 is a perspective view of the portable lamp with detachable stand.

FIG. 2 is a front elevational view of the portable lamp with detachable stand in FIG. 1.

FIG. 3 is a left-side elevational view of the portable lamp with detachable stand in FIG. 1; the right side elevational view being a mirror image thereto.

FIG. 4 is a backside elevational view of the portable lamp with detachable stand in FIG. 1; and,

FIG. 5 is a top plan view of the portable lamp with detachable stand in FIG. 1.

The broken lines are for illustrative purposes only and form no part of the claimed design.
